UNITED STATES PATENT OFFICE.

ALBERT LINN MURRAY, OF AUBURN, INDIANA, ASSIGNOR TO AUBURN RUBBER CO.,
OF AUBURN, INDIANA.

DESIGN FOR A NONSKID TREAD FOR A PNEUMATIC TIRE.

Application filed January 22, 1923. Serial No. 4,964. Term of patent 3½ years.

To all whom it may concern:

Be it known that I, ALBERT LINN MURRAY, a citizen of the United States, residing at Auburn, in the county of De Kalb and State of Indiana, have invented a new, original, and ornamental Design for a Nonskid Tread for Pneumatic Tires, of which the following is a specification, reference being had to the accompanying drawing, forming part thereof.

The Figure (A) is a plan view and the Figure (B) a cross section view of the nonskid tread of a pneumatic tire, showing my new design.

I claim:

The ornamental design for a nonskid tread for a pneumatic tire, as shown.

January 19, 1923.

ALBERT LINN MURRAY.
